UNITED STATES PATENT OFFICE.

JOHN J. HALLIWELL, OF MOUNT VERNON, NEW YORK, ASSIGNOR, BY MESNE ASSIGNMENTS, TO R. HOE AND CO., INC., OF NEW YORK, N. Y., A CORPORATION OF NEW YORK.

LATE-NEWS-PRINTING DEVICE.

Application filed May 17, 1923. Serial No. 639,434.

To all whom it may concern:

Be it known that I, JOHN J. HALLIWELL, a citizen of the United States, residing at Mount Vernon, county of Westchester, and State of New York, have invented certain new and useful Improvements in Late-News-Printing Devices, fully described and represented in the following specification and the accompanying drawings forming a part 10 of the same.

This invention relates to certain improvements in late news printing devices.

These late news printing devices are employed for printing additional matter, such 15 as late news received after the make-up of stereotype plates by which the main portion of the paper is printed. In these late news mechanisms some part of the stereotype plate is left blank, that is, is not provided 20 with a printing surface so that a certain portion of the web is left unprinted after the main portion has been printed or perfected by the usual printing couples. The blank space left in the web after the main 25 printing is generally of small dimensions as the amount of late news matter which would be printed is generally small. In printing this late news difficulty may be experienced in forwarding the web through the late news 30 couple so that the unprinted portion of the web will accurately register with the late news mechanism. Furthermore, in the operation of these late news printing devices it is desirable that the construction be such 35 that the printing may be effected at every revolution of the form member or at alternate revolutions, depending on the place in the paper where the late news printing is to be done.

40 It is one of the objects of the present invention to provide a construction by which the late news printing may be effected either on every revolution of the late news printer or on alternate revolutions without tripping the form cylinder or the impression member co-operating therewith where alternate printing is to be effected during the printing operation, thus producing a simple structure.

45 It is a further object of the present invention to provide means for adjusting the web so as to cause the unprinted portion thereof to pass between the late news printing couple with the unprinted portion of the

web in correct longitudinal relation with the 55 late news printer so that the printing will occur on the web in the correct place.

It is a further object of the invention to improve the general construction of this late news printer whereby the printing relation 60 between the members of the late news printing couple may be entirely stopped when it is not desired to effect the printing action.

It is a further object of the invention to produce a construction which can be readily 65 and simply associated with the other mechanisms of the printing machine.

With these and other objects not specifically referred to in view, the invention consists in certain novel parts, combinations, 70 and arrangements, which will be fully described in connection with the accompanying drawings and the novel features then pointed out in the claims hereunto annexed.

In these drawings—

75 Figure 1 is a side elevation, partly broken away and partly in section of so much of a late news printer as is necessary for an understanding of the invention.

Figure 2 is a partly broken away and 80 partly sectional end view of part of the construction shown in Fig. 1 looking in the direction of the arrow 2 of that figure.

Figure 3 is a detail section on an enlarged scale of the preferred connections for adjusting the web path.

Figure 4 is a somewhat diagrammatic sectional end view of the late news printing couple and the web guides showing the arrangement for printing on alternate revolutions of the form member.

Figure 5 is a side view, partly in section and partly broken away of one arrangement of the impression cylinder and the impression blanket of the late news couple.

Figure 6 is a view similar to Fig. 5 showing another arrangement of the blanket.

Figure 7 is a detail sectional view of a blanket securing device for the blanket shown in Fig. 5.

Referring now to these drawings, the invention has been illustrated as employed in printing late news on a web which has been printed and perfected in the usual manner except for a space in the web which has 105 been left blank for the reception of the late news. As shown there is diagrammatically indicated a pair of printing cylinders 1, 2,

and a pair of perfecting cylinders 3, 4 by which the web W is printed and perfected, these cylinders being mounted as usual in the frames 5 of any suitable or desired construction.

Located adjacent the printing and perfecting mechanisms is the late news printer, this late news printer, in the particular construction illustrated, being mounted above the printing and perfecting couple in suitable frames 7, 8 of any convenient or desired construction. This late news printer may be varied somewhat in construction, but will include an impression cylinder 9 mounted in the side frames 7, 8, before referred to, and a form cylinder 10 together with an appropriate inking mechanism therefor. In printing with these late news printing devices it is frequently desirable that the printing relation between the form and impression cylinders of the late news printer may be interrupted so that no printing shall be effected on the web, and in the best constructions and in accordance with the invention these means will include connections whereby the impression cylinder may be moved out or tripped away from the form cylinder, this construction obviating the necessity of moving the form cylinder and its co-operating inking mechanism. While this tripping mechanism may be of any desired character, in the particular construction shown, the shaft 11 of the impression cylinder 9 is provided with reduced ends 12 mounted in roller bearings 13 located within an eccentric sleeve 14 mounted in the side frame 7, before referred to, and the parts are held in position by a collar 14' secured to the sleeve in any suitable manner, as by set screws 15. The outer end of this sleeve is formed with an arm 16 by which the sleeve can be rotated to trip the impression cylinder on and off an impression.

In the best constructions means are provided whereby the throw of the eccentric may be adjusted, and in the preferred construction these adjusting means are also utilized for rocking the arm. In the particular construction shown there is provided a split arm 17 having members 18, 19, the member 18 being secured to the arm 16. These members are recessed, as indicated in dotted lines in Fig. 1, and are connected by a threaded bolt 20, lock nuts 21 being provided for preventing rotation of the bolt. On the bolt is provided an adjusting nut 22, the lock nuts and the adjusting nut being provided with holes 23 by which they may be turned through the medium of any suitable tool. By rotating this nut 22 parts of the arm are drawn toward and forced away from each other thus rocking the arm and adjusting the impression contact between the form and impression cylinders, and this may be done while the cylinders are in print-

ing contact. The part 19 of the arm 17 is connected to an arm 24 on a rock shaft 25 suitably journaled in extensions 26 of the side frames 7, 8, before referred to, and this shaft is provided with an operating handle 27, by which the shaft may be rocked. The rock shaft 25 carries an arm 24' provided with a slot 28 adapted to take over a pin 29 on the frame of the machine and to be locked to the frame by an operating handle 30. When this handle is in locked position, as shown in Fig. 1, the parts form in effect a toggle, and by operating the handle 27 the impression cylinder may be tripped on impression as shown in Fig. 1. If it be desired to trip the cylinder off impression this may be done in the same way by an arm 31 on the rock shaft 25, this arm having a slotted end 32 taking over a lower pin 33 fast on the frame. With this construction, therefore, the impression cylinder may be moved to stop the printing contact and it is unnecessary to move the form cylinder and its associated inking mechanism.

In order that the blank space left in the printed web and indicated by the letter B on Fig. 2, may come in correct position with respect with the late news printer, means are provided for adjusting the web path so as to properly position the blank space in the web. In the preferred construction as illustrated, these means act to lengthen or shorten the web path, and in the particular construction illustrated, there is provided a roll or pulley 35 over which the web passes on its way from the main printing mechanism to the late news printer. This adjusting roll may be mounted and operated in any suitable manner to shift the web path so as to lengthen or shorten it between the main printing couple and the late news printer. In the particular construction illustrated, this roll is carried on a shaft 36 supported in the ends of a pair of arms 37 fast on a rock shaft 38 journaled in brackets 39 secured to the side frames of the machine. Also fast on this rock shaft behind the arm 37 is an operating arm 40. The lower end of this arm is provided with a threaded aperture to receive a clamp screw 41 by which the arm can be rocked, thus rocking the rock shaft 38 and projecting the roll 35 toward or away from the web, thus increasing or decreasing the length of the web path between the main printing mechanism and the late news printer. Means are provided for locking the arm 40 in its adjusted position, and these means, in the construction illustrated, include a hanger block 42 conveniently secured in the bracket 39 as by loosely mounting it on the end of the rock shaft 38. This hanger block has a depending arm 43 having an adjusting slot 44 in which the clamp screw 41 may have a side to side movement, the screw being

clamped in adjusted position by means of a collar 45 bearing against the side of the arm. With this construction the web path may be very quickly and accurately adjusted, and 5 this adjustment can be effected while the machine is running so that the printing of the late news on the web will take place at the correct point.

The form member of the late news printing couple and its associated inking mechanism are, in the best constructions, mounted and arranged so that they can be moved as a unit across the width of the web when this printing may be effected at any desired 10 point in the web widthwise thereof. In the particular construction shown, this form member is a small cylinder 46 slidably mounted on a shaft 47 extending across the machine and mounted in the side frames 7, 15 8, before referred to, the cylinder being locked to the shaft by means of set bolts 48, this cylinder in the best constructions being capacitated to carry a plurality of small plates 49, these plates being held on the 20 cylinder by spring clamps 50. Co-operating with this cylinder is an inking mechanism including the inking rolls 51, a driven distributing cylinder 52, a ductor roll 53, a fountain roll 54 working in a fountain 55, 25 these parts being movable widthwise of the machine with the printing cylinder.

These parts are driven in any suitable manner as from the main impression cylinder 3 which is provided with a gear 56 meshing with an intermediate 57 which in turn meshes with a gear 58 on the shaft 11 of the impression cylinder 9. This gear 58 is also in mesh with a gear 59 on one end of the shaft 47 of the form cylinder 46 of 30 the late news couple. The other end of this shaft carries a gear 60 which meshes with a gear 61 on a short shaft 62 carried in side frames 63, 64 which are slidable on rods 65, 66 mounted in the frames 7, 8 before referred 35 to, and which thus support the inking mechanism. The shaft 62 at its outer end is provided with a mitre 67 in mesh with a mitre 68 on the lower end of a short vertical shaft 69 journaled in brackets 70 secured to the 40 frame 64. The upper end of this shaft is provided with a worm 71 meshing with a worm wheel 72 on the end of a shaft 73 which supports the fountain roll.

In machines embodying the invention, 45 means will be provided whereby the printing contact between the form cylinder and the co-operating impression cylinder may be effected at each revolution of the form cylinder or at alternate revolutions only, the construction being such that the interruption of the printing is effected without the use of trips so that a simple structure is produced. While this may be effected in various ways, 50 in the particular construction illustrated, the impression cylinder is provided with a non-

impression surface which is conveniently formed by omitting the blanket from one half the cylinder, as shown in Fig. 4. Co-operating with the adjustable guide roll 35, before referred to, and arranged on the other side of the printing couple is a guide roll 73' on a shaft 74 mounted in a bracket 75, the web passing over this guide roll 73' to a folder or other suitable mechanism. The rolls 35 and 73' are so arranged with respect to each other that when the non-impression surface 76 of the impression cylinder is advanced toward the form cylinder the web will fall away, as shown in Fig. 4, and no printing action will be effected for 55 one revolution of the form member. If it be desired to print at every revolution of the form member a blanket is added to the other half of the impression cylinder so that the web is in contact with the form at each 60 revolution.

The blanket or blankets may be of any usual or suitable form and may extend either across the impression cylinder, as shown in Fig. 6, or a narrow blanket, indicated at 77, may be used which is movable to any position across the cylinder, being supported at one end in a slotted rod 78 and at its other end on pins 79.

The web after it passes the late news 65 printer may pass over a guide roll 73' to a folder or other suitable mechanism.

While the invention has been shown and described in its preferred form, it will be understood that certain changes and variations may be made in the specific structure illustrated and described, and that the invention is not to be restricted to such structure.

What I claim is:

1. In a late news printing machine, the combination of a late news printing couple, including a narrow form cylinder and a wide impression cylinder, and means for moving the form cylinder along the impression cylinder, said impression cylinder being of greater diameter than the form cylinder and capacitated to carry a blanket on each half of its circumference, that surface of the cylinder from which a blanket may be removed forming a non-impression surface, whereby the mechanism may be arranged to print on each revolution of the form cylinder or on alternate revolutions.

2. In a late news printing machine, the combination of a printing couple for printing the major portion of a web, a late news printing mechanism, including a narrow form cylinder and a wide impression cylinder, means for moving the form cylinder across the impression cylinder, means for adjusting the web between the main printing couple and the late news printer to effect accurate printing in the unprinted portion of the web, and means whereby the late

news printer may be arranged to print on every revolution of its members or on alternate revolutions.

3. In a late news printing mechanism, the combination of a printing couple for printing the major portion of a web, a late news printing couple for printing in an unprinted portion of the web, one member of said couple being provided with a non-impression surface, and web guides including an adjustable roll for guiding the web through the late news couple so that the web may pass freely between the members of the couple and receive no impression on alternate revolutions of the printing member of the couple.

4. In a late news printing mechanism, the combination of a printing couple for printing the major portion of the web, a late news printing couple for printing in an unprinted portion of the web, one member of said couple being provided with a non-impression surface, and web guides for guiding the web through the printing couple, so that the web may pass freely between the members of the couple and receive no impression on alternate revolutions of the printing member of the couple.

5. In a late news printing mechanism, the combination of a printing couple for printing the major portion of the web, a late news printing couple for printing in an unprinted portion of the web, one member of said couple being provided with a non-impression surface, web guides for guiding the web through the printing couple, so that the web may pass freely between the members of the couple and receive no impression on alternate revolutions of the printing member of the couple, and means for adjusting the length of the web path between the main printing couple and the late news printer.

6. In a late news printing machine, the

combination of a late news printing couple, including a narrow form cylinder, a wide impression cylinder, means whereby the form cylinder may be moved along the impression cylinder, a narrow blanket on the impression cylinder, and means for positioning the blanket at different points widthwise of the impression cylinder.

7. In a late news printing machine, the combination of a late news printing couple including a narrow form cylinder, an impression cylinder of greater diameter than the form cylinder, and a blanket on one half of the circumference of the impression cylinder, the unblanketed portion of the impression cylinder forming a nonimpression surface.

8. In a late news printing machine, the combination of a late news printing couple including a narrow form cylinder, a wide impression cylinder of greater diameter than the form cylinder, means whereby the form cylinder may be moved along the impression cylinder, a narrow blanket on one half of the circumference of the impression cylinder, the unblanketed portion of the impression cylinder forming a nonimpression surface, and means for positioning the blanket at different points widthwise of the impression cylinder.

9. In a late news printing machine, the combination of a late news printing couple including a narrow form cylinder, a wide impression cylinder, means whereby the form cylinder may be moved along the impression cylinder, the axes of the cylinders being fixed during the printing cycle, and means whereby the printing relation between the form and impression cylinders takes place on alternate revolutions only of the form cylinder.

In testimony whereof, I have hereunto set my hand.

JOHN J. HALLIWELL.
